JOHN T. CARROLL, OF BALTIMORE, MARYLAND, ASSIGNOR TO FRANKLIN RAILWAY SUPPLY COMPANY, OF NEW YORK, N. Y., A CORPORATION OF DELAWARE

REVERSE GEAR

Application filed May 12, 1926. Serial No. 108,465.

My invention relates to reverse gear equipment for locomotives, and particularly to such equipment either for what are known as "double" locomotives, or for those which expand the steam in successive stages, such as 5 the Mallet compound locomotives. In the first type mentioned there are two sets of cylinders which receive steam independently of each other, while in the second there is a high pressure cylinder and a low pressure cylinder 10 with the exhaust from the former going to the latter.

I aim to improve the operation of such locomotives by permitting one set of cylinders to be run with a cut-off different from 15 that of the other, according to what is required for the most economical or efficient operation of the locomotive at the time.

For instance, in a double engine, difficulty 20 is sometimes had in preventing the front engine from slipping, and, with the reverse gear equipment now in use, a shortening of the cut-off to control this slippage at the same time operates to limit the work being done 25 by the second engine. Also, in compound engines, if a short cut-off were being used, the amount of steam reaching the receiver would be smaller than if a longer cut-off were being used, although there might, at the same 30 time, be many conditions under which it would be desirable to keep the receiver pressure up to some higher point. With my invention, the foregoing difficulties can be overcome, for I provide a double reverse gear 35 equipment with which it is possible to work the front engine of a double locomotive at a shorter cut-off than the second engine, or to so proportion the cut-offs of a compound engine as to maintain any desired pressure in 40 the receiver. How the foregoing and other advantages can be realized through the invention will appear from my description of a selected and preferred embodiment.

In the drawings—

Fig. 1 is a fragmentary and diagrammatic side view of a locomotive equipped with a double reverse gear conveniently embodying my invention.

Fig. 2 is a side view of the hand levers for 50 operating the gear shown in Fig. 1.

Fig. 3 is a view at right angles to Fig. 2, from the left of that figure.

Fig. 4 is a diagrammatic side view of a locomotive including a showing of cylinders of two sets with portions of their associated 55 valve mechanisms and the connection from the latter to the double reverse gear of the present invention.

As an example, it is assumed that a compound locomotive is represented in the drawings. It is equipped with a double power-operated reverse gear, comprising motors 4, 5, whose cross-heads are connected by links 6, 7, to the usual rocker-arms 8, 9, from which the valve motions of the high and low pressure engines of the locomotive may be adjusted in the usual manner. Cylinders of the two engines are indicated, in Fig. 4, by the reference letters A and B while portions of the associated valve mechanisms are somewhat 60 diagrammatically indicated at C and D. The motors 4, 5, are controlled from the locomotive cab 10 through reach-rods 12, 13, connected to the upper ends of the floating valve-operating levers 14, 15, and are provided 65 with follow-up connections 16, 17, from their cross-heads to the lower ends of said levers 14, 15. In the cab 10, the rods 12, 13, are connected to control mechanism 19, shown as 70 manually operated.

As shown in Figs. 2 and 3, the control mechanism 19 comprises a main hand lever 20 provided with a hand latch 21 for cooperation with a toothed quadrant 22, so that it may be stably "set" in any desired position, from 75 "full-gear forward" to "full gear backing". In Fig. 2, this lever 20 is shown in neutral or "mid gear" position. In the present instance, this main lever 20 is fast to one end of a short shaft 23 suitably journalled in a 80 sleeve 24 of a main supporting bracket casting 25, that also carries the quadrant 22. Fast to the other end of the shaft 23 is a lever or arm 26, to which the rod 12 for the valve motion of the high pressure engine is 85 connected by a pivot bolt 27. By operation of this main lever 20, therefore, the valve-motion of the high-pressure engine may be adjusted and set as usual.

As shown in Figs. 2 and 3, the rod 13 for 90

the valve-motion of the low-pressure engine is connected by a pivot stud 28 to an adjusting lever 30 that is fulcrumed on the bolt 27 in the arm 26. This lever 30 is provided with a hand latch 31 for cooperation with a toothed sector 32 carried by the arm 26.

It will be seen, therefore, that the lever 30 and its sector 32 may move bodily with the main lever 20; so that whenever the valve motion of the high pressure engine is adjusted, that of the low pressure engine is correspondingly adjusted. In addition, the low-pressure valve motion can be adjusted (to a limited extent) with reference to the high pressure valve motion, by adjusting the lever 30 forward or backward along the sector 32. Thus, the cut-off of the low-pressure engine can be made either earlier or later than that of the high-pressure engine by practically any amount desired, as may be necessary to give the best efficiency under various conditions. Once it has been determined by adjustment of the lever 30, however, this cut-off differential will be automatically maintained in the subsequent adjustment of the high-pressure cut-off by the main lever 20; because the adjustment of the low pressure valve motion is automatically correlated with that of the high pressure valve motion by the latch and sector connections 31, 32.

The advantages of such a double adjustment may be made clearer by the following considerations.

If conditions are such that the high pressure engine can most advantageously be run on a short cut-off, then the amount of steam reaching the receiver between the high and low pressure cylinders will be smaller than for a longer cut-off; so that in order to keep up the receiver pressure and prevent it from dropping below atmospheric, the low pressure engine may and can be operated on a shorter cut-off than the high pressure engine. When, on the other hand, the high pressure engine is operated on a long cut-off, the amount of steam reaching the receiver may be so great as to make it advisable to operate the low pressure engine on an even longer cut-off, in order to prevent an excessive pressure from building up in the receiver.

Thus, it will be seen, my invention allows the high pressure engine to be operated in the manner best suited to its own requirements, without any consideration for the low pressure engine, which can always be operated in the way that will utilize the steam supply from the high pressure engine most advantageously.

Similarly, with practically identical equipment, it is possible with my invention to control the cut-offs of a "double" engine so that one set of cylinders can be operated at a cut-off different from that of the other, as may best suit the conditions obtaining at the moment.

I claim:

1. A reverse gear equipment for locomotives having two sets of cylinders with separate valve motions, comprising a main bearing, a shaft journalled in said bearing, a lever carried by said shaft, an arm also carried by said shaft, a second lever pivotally supported upon said arm and arranged for angular adjustment with respect to said first-mentioned lever, and a pair of valve-setting rods respectively connected to said arm and to said second lever. 70 75

2. A reverse gear equipment for locomotives having two sets of cylinders with separate valve motions comprising a main bearing, a shaft journalled in said bearing, a lever carried by said shaft, an arm also carried by said shaft, a second lever pivotally supported upon said arm and arranged for angular adjustment with respect to said first-mentioned lever, a pair of valve-setting rods respectively connected to said arm and to said second lever, and means carried by said bearing and operatively associated with said first-mentioned lever for maintaining both of said levers in adjusted position. 80 85 90

3. In a locomotive having two sets of cylinders with separate valve motions the combination of a reverse lever, an arm moving therewith, a lever adjustably pivoted to said arm and means for connecting the arm with one of the valve motions and the second mentioned lever with the other valve motion. 95

4. In a locomotive having two sets of cylinders with separate valve motions the combination of a reverse lever, an arm moving therewith, a lever adjustably pivoted to said arm and means for connecting the arm with one of the valve motions and the second mentioned lever with the other valve motion including a pair of power reverse gears. 100 105

5. In a locomotive having two sets of cylinders with separate valve motions the combination of an adjustable reverse lever, an arm moving therewith, a lever adjustably pivoted to said arm and means for connecting the arm with one of the valve motions and the second mentioned lever with the other valve motion, together with means for retaining said reverse lever and the arm in adjusted position. 110 115

6. In a locomotive having two sets of cylinders with separate valve motions the combination of a manually operable valve motion reversing member, means connecting said member with one of said motions, a lever carried by and adjustable with respect to said member and means connecting said lever with the other of said motions. 120

7. In a locomotive having two sets of cylinders with separate valve motions the combination of a manually operable valve motion reversing member, means connecting said member with one of said motions, a lever carried by and adjustable with respect to said 125 130

1,833,483

member and means connecting said lever with
the other of said motions, said connecting
means including a pair of power reverse
gears.

⁵ In testimony whereof I have hereunto
signed my name. JOHN T. CARROLL.
